FIG. 9

FIG. 7

INVENTOR.
Philip Palmer
BY Emanuel Scheyer
Attorney

1. A cap lifter tool having a handle and a shank, the outer edge of the shank being provided with a shallow notch which gives rise to two prongs, the prongs being relatively wide at their base in comparison to their height, so that they offer great resistance to bending and distortion, the provision of the notch enabling the outer edge of the shank to be thrust under the cap without being blocked by the curvature of the neck of the jar, the notch providing space for the curve.

This invention relates to a cap lifter which is especially adapted for readily and quickly removing the well-known vacuum sealed metal tops from glass vacuum jars. Caps and jars of other materials can also be operated upon. Friction gripped caps can also be removed from containers provided they are of a fit and form suitable for the lifters. My lifter removes the cap with little effort and without damage to the cap so that it can be readily replaced.

The lifter consists essentially of a handle and a shank, the outer edge of the shank being provided with a shallow notch which gives rise to prongs. The prongs are relatively wide at their base in comparison to their height, so that they offer great resistance to bending and distortion. The provision of the notch enables the outer edge of the shank to be thrust under the cap without being blocked by the curvature of the neck of the jar, the notch providing space for the curve.

A line joining the apices of the prongs is substantially parallel to the long axis of the handle. When the handle is turned about an axis midway between the prongs and perpendicular to said long axis, great leverage is obtained for lifting the cap. When the lifter is inserted under the cap and the handle is turned, one prong bears down on the shoulder of the jar and the other prong pushes up on the cap. The lifting action of the prongs is assisted by having one or both prongs bent out of the plane of the surfaces of the shank. The prongs are so bent out from the handle or shank that they are given a hook shape. When one or both prongs are so hooked, the portion of the prong under the cap is prevented from being pushed out as the handle is turned for lifting the cap. In my preferred form both prongs are hooked, so that no matter which way the lifter is inserted under the cap, there is always a hooked prong in contact with the lower edge of the cap.

By having the side edges of the shank at the prongs extend substantially parallel to the aforementioned axis of rotation of the prongs when lifting the cap, or by having said edges undercut or relieved the tool may be rotated about said axis of rotation without a tendency for the shank to slip out from under the cap.

Other objects and advantages will become apparent upon further study of the description and drawings in which:

Fig. 1 is an elevation of a form of cap lifter having a handle of wood, plastic or other suitable material.

Fig. 2 is an end view of Fig. 1 looking along the

line of the axis of rotation of the prongs of Fig. 1, showing a form in which only one prong is inclined to the general plane of the shank.

Fig. 3 is an end view taken similarly to Fig. 2, but showing a modified form in which both prongs are inclined to the general plane of the shank.

Fig. 4 is a plan view of a form of cap lifter in which the handle is of sheet material and integral with the shank. The shank extends from the middle portion of the length of the handle.

Fig. 5 is a plan view of a form of cap lifter in which the handle is of wood, plastic or other suitable material, with the shank projecting from the mid-portion of the handle.

Fig. 6 is a perspective view of a form of cap lifter in which the handle is of sheet metal which is looped back on itself and is integral with the shank.

Fig. 7 is a plan view of a jar and cap shown with the prongs of the cap lifter inserted under the cap, a portion of the handle of the lifter being broken away.

Fig. 8 is a section taken along the line 8—8 of Fig. 7, the bottom portion of the jar being broken away, and

Fig. 9 is a section taken similarly to Fig. 8 except that the lifter has been rotated effecting a partial removal of the cap.

The lifter of Figs. 1, 2, 7, 8, and 9 is provided with a handle 10 in which the tail portion 14 of shank 11 is rigidly mounted. The outer edge of shank 11 is provided with a shallow notch 15 which gives rise to pointed prongs 12 and 13. These prongs are generally in the form of a right angled triangle in which the apices are at or near the side edges 16 of the shank. Prong 12 has one of its surfaces in the plane of and as a direct continuation of one of the surfaces of shank 11. The other surface of prong 12 is also a direct continuation of the other surface of shank 11, except that it curves inward to reduce the edge thickness of the prong for easy insertion under cap 17 of jar 18.

With prongs 12 and 13 inserted under cap 17, handle 10 is turned counter-clockwise. The great leverage of handle 10 applied to said prongs, prong 12 being in contact with shelf 19 of jar 18 and prong 13 which is bent out into a hook from shank 11, being in contact with cap 17, readily lifts the cap off the jar as seen in Fig. 9. The shape of the hook is such that prong 13 can have a surface inserted under the lower edge of the cap with its outer end coming higher than said edge when the lifter is in position to lift the cap,

line 2—2 of Fig. 1, showing a form in which only one prong is inclined to the general plane of the shank.

Fig. 3 is an end view taken similarly to Fig. 2, but showing a modified form in which both prongs are inclined to the general plane of the shank.

Fig. 4 is a plan view of a form of cap lifter in which the handle is of sheet material and integral with the shank. The shank extends from the middle portion of the length of the handle.

Fig. 5 is a plan view of a form of cap lifter in which the handle is of wood, plastic or other suitable material, with the shank projecting from the mid-portion of the handle.

Fig. 6 is a perspective view of a form of cap lifter in which the handle is of sheet metal which is looped back on itself and is integral with the shank.

Fig. 7 is a plan view of a jar and cap shown with the prongs of the cap lifter inserted under the cap, a portion of the handle of the lifter being broken away.

Fig. 8 is a section taken along the line 8—8 of Fig. 7, the bottom portion of the jar being broken away, and

Fig. 9 is a section taken similarly to Fig. 8 except that the lifter has been rotated effecting a partial removal of the cap.

The lifter of Figs. 1, 2, 7, 8, and 9 is provided with a handle 10 in which the tail portion 14 of shank 11 is rigidly mounted. The outer edge of shank 11 is provided with a shallow notch 15 which gives rise to pointed prongs 12 and 13.

These prongs are generally in the form of a right angled triangle in which the apices are at or near the side edges 16 of the shank. Prong 12 has one of its surfaces in the plane of and as a direct continuation of one of the surfaces of shank 11. The other surface of prong 12 is also a direct continuation of the other surface of shank 11, except that it curves inward to reduce the edge thickness of the prong for easy insertion under cap 17 of jar 18.

With prongs 12 and 13 inserted under cap 17, handle 10 is turned counter-clockwise. The great leverage of handle 10 applied to said prongs, prong 12 being in contact with shelf 19 of jar 18 and prong 13 which is bent out into a hook from shank 11, being in contact with cap 17, readily lifts the cap off the jar as seen in Fig. 9. The shape of the hook is such that prong 13 can have a surface inserted under the lower edge of the cap with its outer end coming higher than said edge when the lifter is in position to lift the cap,

55

that is when prong 13 contacts said lower edge and prong 12 is pressed down against shelf 19 of jar 18.

Fig. 3 shows a modification of the lifter of Figs. 1 and 2 in which both prongs 20 and 21, while forming direct continuations of the surface of the shank are bent out of the plane of these surfaces into a hook, the inclination of prong 20 being opposite to the inclination of prong 21. The shape of both prongs 20 and 21 is similar to that already described for prong 13. The configuration of the surfaces of the prongs contacting the lower edge of the cap is such that lines can be drawn in them which are substantially perpendicular to the direction in which the prongs extend from the shank. The direction in which the prongs extend is toward the top of the sheet in Fig. 1. Further, said lines are parallel to the surfaces or general plane of shank 11. Prong 13 of Fig. 2 has its surface for contacting the cap also of the above noted configuration.

In Fig. 4, shank 22 is a direct continuation and integral with handle 23. Prongs 12 and 13 are formed on the outer edge of shank 22, just the same as they are formed on the outer edge of shank 11, Figs. 1 and 2. Handle 23, shank 22 and prongs 12 and 13 are all one sheet metal piece. The edges of prongs 12 and 13 on their sides away from each other are undercut or relieved. The edges referred to are the left edge of prong 12 and the right edge of prong 13. The undercutting improves the hooking action of the prongs under the cap.

In Fig. 5, shank 25 is set in a transverse elongated handle 24 of wood, plastic or other suitable material. Prongs 12 and 13 are the same as in Figs. 1 and 2.

In Fig. 6, handle 26 is a direct continuation and integral with shank 27, said handle being formed of a sheet metal strip which is looped back on itself. Prongs 12 and 13 are also the same as in Figs. 1 and 2.

It will of course be understood, that prongs, inclined as prongs 20 and 21, can be used in the lifters of Figs. 4, 5 and 6.

I claim:

5 A lifter, for a cap used as the closure of a container in which the cap has a skirt at its lower edge setting radially out away from the container, the container being provided with a radially extending portion just below the skirt, comprising a sheet metal shank and a pair of prongs near each other extending away from the shank, one prong having both its surfaces inclined to the surfaces of the other prong, at least one of said surfaces of each prong being concave to enable the concave surface of one prong to be inserted under the lower edge of the cap with the outer end of a prong so inserted higher than the lower edge of the cap while the other prong engages the radially extending portion of the container, said concave surface of one prong facing substantially in the opposite direction and away from said concave surface of the other prong.

PHILIP PALMER.
